UNITED STATES PATENT OFFICE.

ZAE E. PRICKETT, OF CHICAGO, ILLINOIS.

TYPE-WRITER RIBBON-SPPOOL.

1,003,791.

Specification of Letters Patent. Patented Sept. 19, 1911.

Application filed January 26, 1911. Serial No. 604,720.

To all whom it may concern:

Be it known that I, ZAE E. PRICKETT, a citizen of the United States, residing in Chicago, in the county of Cook and State of Illinois, have invented a new and useful Improvement in Type-Writer Ribbon-Spools, of which the following is a specification.

My invention relates to improvements in typewriter ribbon spools.

Heretofore typewriter ribbon spools have ordinarily been made with the metal disks of the spool rigidly fixed to the hub portion thereof: and a good deal of difficulty is experienced in affixing the end of the ribbon to the fastener at the hub of the spool on account of the relatively large diameter of the spool disks and narrow space between them. And in the old construction, it is entirely impossible to remove or apply the ribbon without unwinding it from end to end or rewinding it.

The object of my invention is to provide an improved construction of typewriter ribbon spool by which the objections or difficulties heretofore experienced may be entirely overcome, and which at the same time will be of a simple and efficient construction, capable of being cheaply manufactured.

My invention consists in the means I employ to practically accomplish this object or result as herein shown and described; the same consisting essentially in providing the hub of the spool with means for removably attaching one of the disks thereto, so that the ribbon in coiled form may be slipped onto or off of the hub and to facilitate the fastening of the inner end of the ribbon to the pawl or holding device with which the hub of the spool is furnished for securing the end of the ribbon thereto.

My invention also consists in the novel construction of parts and devices and in the novel combinations of parts and devices herein shown and described and more particularly specified in the claims.

In the accompanying drawing forming a part of this specification, Figure 1 is a plan view of a typewriter ribbon spool embodying my invention. Fig. 2 is a section on line 2-2 of Fig. 1. Fig. 3 is a detail plan view of the removable disk of the spool. Fig. 4 is a section on line 4-4 of Fig. 2. Fig. 5 is a detail elevation of the spool, showing the pawl or holder for the end of the ribbon on the hub of the spool and Fig. 6 is a detail view showing the end of the ribbon with the

customary hook thereon for securing it to the hub of the spool.

In the drawing, 1 represents the hub of the spool, 2 the disk permanently secured or riveted to one end of the hub, 3 the removable disk of the spool, 4 the fastener lips or lugs with which the end of the spool is provided for removably securing the disk 3 thereto, the disk being provided with diametrically opposite slots or notches 5 for the fastener lips 4 to pass through, and a portion 6 of reduced diameter forming a shoulder 7 for the spool disk 3 to fit against. After the removable spool disk 3 is applied to the hub, it is given a slight axial rotation or turning movement to cause the fastener lips 4 on the hub to overlap the inner edge of the spool disk surrounding the opening 8 which receives the reduced portion 6 of the hub.

The hub is provided with the customary recess or cut-away portion 9 and pawl or fastener 10 to receive the hook 11 at the inner end of the ribbon 12.

To secure the hook 11 over the notched portion 13 of the pawl or fastener 10 in applying a ribbon to the spool, it is only necessary to give the removable disk 3 a slight turn to bring the fasteners 4 on the spool into registry with the notches 5 of the disk 3 and then the disk may be removed and the end of the ribbon very easily hooked around the pawl or other fastener 10, and then the ribbon may be wound upon the spool in the old way, or it may be slipped in coiled form over the end of the hub and then the removable disk 3 is applied.

The outer face of the lips or fasteners 14 is preferably flush with the outer end face of the reduced end portion 6 of the spool hub so that the fasteners 4 will not interfere with the application of the spool to the machine either face down.

To remove an old or worn out ribbon from my improved spool it is only necessary to give the removable disk 3 a partial turn and then take it off the hub, when the old ribbon may be very easily and quickly dropped off or removed from the spool hub without unwinding the ribbon from end to end, as has heretofore been required.

I claim:

1. In a typewriter ribbon spool, the combination with a spool disk and hub permanently secured together, said hub provided with a recess and a ribbon hook of a

removable disk on the opposite end of the hub, the hub having at said opposite end fastener lips, and the removable disk having notches to receive said fastener lips, substantially as specified.

2. In a typewriter ribbon spool, the combination with a spool disk and hub permanently secured together, said hub having a shouldered and reduced end and provided with fastener lips flush with the end

face of the reduced end of the hub, and a removable flat disk of uniform thickness having notches adapted to be brought into and out of registry with said lips of the hub by the turning of the disk, substantially as specified.

ZAE E. PRICKETT.
